(57) **CLAIM**

The ornamental design for a cabin floor, as shown and described.

DESCRIPTION

FIG. 1 is a perspective view of the cabin floor showing our new design in an environment of use in an aircraft cabin with seats removed;

FIG. 2 is a perspective view of the cabin floor of FIG. 1 shown in an environment of use in an aircraft cabin with seats removed;

FIG. 3 is a top view of the cabin floor of FIG. 1 shown in an environment of use in an aircraft cabin with seats removed;

FIG. 4 is a top view of the cabin floor of FIG. 1 shown with the environment removed for clarity of disclosure;

FIG. 5 is a perspective view of the cabin floor of FIG. 1 shown with the environment removed for clarity of disclosure; and,

FIG. 6 is another perspective view of the cabin floor of FIG. 1 shown with the environment removed for clarity of disclosure.

In FIGS. 1-6, broken lines indicate environmental structure that forms no part of the claimed design.
